UNITED STATES PATENT OFFICE.

ALBERT AICHELE, OF BADEN, SWITZERLAND.

LIQUID RESISTANCE.

1,082,721.

Specification of Letters Patent. Patented Dec. 30, 1913.

Application filed August 8, 1913. Serial No. 783,746.

To all whom it may concern:

Be it known that I, ALBERT AICHELE, a citizen of the Swiss Republic, and residing at Baden, Switzerland, have invented certain new and useful Improvements in and Relating to Liquid Resistances, of which the following is a specification.

This invention relates to liquid resistances. Such resistances have, compared with metal resistances, the advantage of being more simple in construction and cheaper in cost and they have a large field of use in electrical engineering for use in starting and regulating motors. Those types which have hitherto been in vogue, are however, almost all of them only suitable for hand use, and are either of little or no use for automatic regulation. Nevertheless attempts have been made to effect automatic regulation with these types and their disadvantages have necessarily had to be put up with.

If the electrodes are made movable and are dipped from above into the liquid, then flexible supply cables are required which necessitate continuous watching, or if sector shaped electrodes are employed and rotated, it is necessary to have rubbing rings and brushes which must likewise be kept continuously in good condition.

The well known arrangement in which the level of the liquid in a stationary vessel provided with fixed electrodes is varied by pumping, is not adapted for use where it is desired to vary the amount of the resistance with any degree of quickness.

The object of the invention is to provide an improved liquid resistance.

The invention consists in a liquid resistance which allows on the one hand an almost instantaneous variation of the amount of the resistance and avoids on the other hand constructional parts requiring watching, such as flexible leads, rubbing brushes or insulated vessels.

The invention also consists in a liquid resistance with the electrodes stationary and the electrolyte movable.

The invention also consists in a resistance as referred to above with means for maintaining the level of the electrolyte constant.

Referring to the accompanying diagrammatic drawings, Figure 1 shows a resistance in cross section according to one form of the present invention, and Figs. 2 and 3 show modifications in cross section with

means for maintaining constant the level of the electrolyte.

The form of the invention shown in Fig. 1 consists of a fixed upper box *a* which is closed at the top by a plate. This box projects into the lower movable vessel *b* which contains liquid, in such a manner that its lower edge will form a liquid seal even when the vessel *b* is in its lowest position. The electrode plates *c* are fixed in an insulated manner for instance to insulators in the interior of the box *a*. Current is supplied at *h*. The box *b* is suspended on ropes or chains which pass over fixed pulleys *f* and it is balanced by means of counter weights *g*. It can be raised and lowered by suitable means, so that the electrodes *c* will dip to a greater or less depth into the resistance liquid. In such an arrangement the air may escape or may enter through the pipe *e* which serves also as a discharge pipe for the generated vapor.

The apparatus shown in Fig. 2 consists of a lever *p* adapted to move about a fixed center *q* in the upper box *a*; at its free end it carries the float *o*. The lever *p* has fixed to it a pin *r* on which a two-armed lever *s* can rotate. One end of this lever is guided constrainedly in a slotted link *t* fixed to the lower vessel *b*. The other end of the lever *s* is connected at *v* to a rod *u* by means of which the cock *l* can be operated for supplying water through the pipe *k* which is branched off from the filling pipe *i*. The slotted link *t* is so dimensioned and adjusted that while the volume of the water remains constant, notwithstanding the different vertical heights of the vessel *b*, the movements of the levers *p* and *s* will combine together in such a manner that the point *v* will not move and therefore the cock *l* will remain closed. When a loss of water occurs through the overflow or through evaporation, the sinking of the float *o* will lower the pivot *r* of the lever *s* and therefore also the end *v* of the lever. The cock *l* will then be opened and water will flow in until the normal volume has been restored.

In the arrangement illustrated in Fig. 3 the cock *l* is connected by means of the rod *u* to the float lever *p* at *q*. This lever as in Fig. 2 carries a lateral pin *r* on which the lever *s* can turn. One end *t* of the lever *s* is mounted on the movable lower vessel *b*, but in this case only so as to be capable of

rotation and not capable of a sliding movement, while its other end *v* is pivotally secured to the upper box *a*. The slotted link guide is in this case replaced by a practically equivalent radius link guide. The radius link *w* is fixed at its fixed pivot *z* on the upper box *a*, while its free end is connected to the end *v* of the lever *s* and rocks along the circle indicated. When the 10 lower vessel *b* is raised or lowered together with the center of rotation *t*, the levers will rock on the points *q* and *v*, their relative motion to each other being limited only to the relative difference of height of the liquid 15 level corresponding to the displacement. If, however, the liquid level sinks due to evaporation or leakage, while the lower vessel *b* is stationary, the system of levers *s* *w* will remain at rest, and the lever *p* will turn 20 on the point *r* and thereby open the cock *l*.

It will be understood that the forms of the invention described above are given by way of example only and modifications may be made.

25 Having now described my invention what I claim as new and desire to secure by Letters Patent is:

1. A regulable liquid resistance comprising a fixed upper box or frame provided 30 with electrodes, and a vertically movable lower vessel containing the resistance liquid, said lower vessel being capable of being raised and lowered for the purpose of varying the amount of resistance; as set forth.

35 2. A regulable liquid resistance comprising a fixed upper box or frame provided with electrodes, and a vertically movable lower vessel containing the resistance liquid, said lower vessel being counter-balanced and 40 being capable of being raised and lowered for the purpose of varying the amount of resistance; as set forth.

45 3. A regulable liquid resistance comprising a fixed upper box or frame provided with electrodes and a vertically movable lower vessel containing the resistance liquid, means closing said box, a discharge pipe for air and vapor situated at the top in said means while its lower part dips into the 50 liquid in all working positions of the liquid vessel, and forms a water seal, as set forth.

55 4. A regulable liquid resistance comprising a fixed upper box or frame provided with electrodes and a vertically movable lower vessel containing the resistance liquid, said lower vessel being capable of being raised and lowered for the purpose of vary-

ing the amount of resistance, together with devices capable of maintaining a constant level of the liquid, comprising a float valve 60 for the inflow and an overflow pipe for the outflow of the liquid; as set forth.

5. A regulable liquid resistance comprising a fixed upper box or frame provided with electrodes and a vertically movable 65 lower vessel containing the resistance liquid, said lower vessel being capable of being raised and lowered for the purpose of varying the amount of resistance, together with devices capable of maintaining a constant 70 level of the liquid, as set forth.

6. A regulable liquid resistance comprising a fixed upper box or frame provided with electrodes and a vertically movable 75 lower vessel containing the resistance liquid, said lower vessel being capable of being raised and lowered for the purpose of varying the amount of resistance, together with devices capable of maintaining a constant level of the liquid comprising two levers, 80 one of which carries a float, while the other operates a device for shutting off the water supply, the one lever being rotatable about a point which is fixed or movable in the upper box, while the other lever is rotatable 85 about a point that is fixed or movable in the lower vessel whereby the device for shutting off the supply is opened only by the variation of the amount of liquid and not by the rise and fall of the liquid vessel; as set forth. 90

7. A regulable liquid resistance comprising a fixed upper box or frame provided with electrodes, and a vertically movable lower vessel containing the resistance liquid, said lower vessel being capable of being 95 raised and lowered for the purpose of varying the amount of resistance, together with devices capable of maintaining a constant level of the liquid, comprising a float fixed on the end of a one-armed lever rotatable 100 about a fixed point in the upper box said lever carrying a pivot for a further two-armed lever, one end of which is guided constrainedly in a slotted link fixed to the movable lower vessel while its other end 105 operates a device for shutting off the water supply; as set forth.

In testimony whereof, I affix my signature in presence of two witnesses.

ALBERT AICHELE.
